UNITED STATES PATENT OFFICE.

EMIL YOUNGQUIST, OF DULUTH, MINNESOTA.

WEATHER-STRIP FOR DOORS.

1,149,108.

Specification of Letters Patent.

Patented Aug. 3, 1915.

Application filed July 21, 1914. Serial No. 852,231.

To all whom it may concern:

Be it known that I, EMIL YOUNGQUIST, a citizen of the United States, residing at Duluth, in the county of St. Louis and State of Minnesota, have invented new and useful Improvements in Weather-Strips for Doors, of which the following is a specification.

The invention relates to automatically operated thresholds, and more particularly to the class of weather strips for doors.

The primary object of the invention is the provision of a strip of this character wherein on the closing of the door the said strip is automatically lowered to absolutely close the gap between the sill of the doorway and the lower edge of the door.

Another object of the invention is the provision of a strip of this character which enables the dispensing with the old or ordinary form or style of threshold which is usually nailed to the floor and is inconvenient as it will wear out, leaving an opening for the creation of a draft therethrough, the strip being automatically controlled on the opening and closing of the door.

A further object of the invention is the provision of a strip of this character which is simple in construction, automatically operated, thoroughly reliable and efficient in its purpose, and inexpensive in manufacture and installation.

With these and other objects in view, the invention consists in the construction, combination and arrangement of parts as will be hereinafter fully described, illustrated in the accompanying drawing, and pointed out in the claim hereunto appended.

In the drawings:—Figure 1 is a fragmentary front elevation of a door frame and door, showing the strip constructed in accordance with the invention applied and in closed position. Fig. 2 is a horizontal transverse sectional view through the doorway and door showing the device applied. Fig. 3 is a fragmentary sectional view on the line 3—3 of Fig. 2. Fig. 4 is a sectional view on the line 4—4 of Fig. 2. Fig. 5 is a perspective view of one of the housing plates for the device.

Similar reference characters indicate corresponding parts throughout the several views in the drawings.

Referring to the drawing in detail, A designates a portion of a door frame, B the floor sill line thereof, and C the swinging

door, which is of the ordinary well-known construction.

Formed in the lower edge of the door C is a vertical guide way 10 in which is fitted the adjustable weather strip or threshold, comprising a board or plate 11 which is slidably fitted within the door frame 10, and has mounted on opposite ends thereof toothed racks 12 with which respectively mesh the toothed sector 13 and gear 13' which are secured upon a single shaft 14 common thereto, the latter being journaled in bearing plates 15 secured to the door C, the latter being cut away in its lower edge to accommodate the shaft 14 so that the sector 13 and gear 13' will lie within the lower edge 70 of the door.

Mounted on the inner face of the door C, and at the free vertical edge thereof is a facing plate 16, the same being formed at 75 its corner with a slot 17 for receiving a stationary operating rack 18 disposed horizontally and fixed to the side of the door frame A so that its teeth will project into the path of the teeth on the rack gear 13' for operating the same during the opening and closing movements of the door for the retracting or extending of the board or plate 11 automatically, as will be apparent.

Connected to the sector 13 concentrically 85 with respect to the shaft 14 is a member 19 to which is connected one end of a coiled retractile spring 20, the other end of which is connected to the door, and this spring serves to hold the board or plate 11 raised or 90 elevated after the rack 18 has disengaged the gear 13' upon the opening of the door. Carried in the lower edge of the board or plate 11 is a rubber strip 21 to prevent the entrance of moisture from the outside to a 95 room or inclosure when the board or plate 11 has been automatically lowered on the closing of the door.

In the operation of the strip or threshold when the door is opened and is being closed, 100 the instant the stationary rack 18 engages with the gear 13' the latter is rotated and acts upon the rack bar meshing therewith, causing the board or plate 11 to be automatically lowered and to contact with the 105 floor or sill line of the door frame when the door has been completely closed. Now, when the door is opened the gear 13' is 110 reversely rotated, thereby raising the board or plate 11 and conceals the same within the

guideway 10 in the lower edge of the door, the spring 20 being designed to hold the board or plate in its elevated position in the guideway until the door is again closed. It is of course understood that the board or plate 11 can be readily removed from the guideway should it be desired, and this is preferable during summer months.

From the foregoing it is thought that the construction and manner of operation of the device will be clearly understood, and therefore a more extended explanation has been omitted.

What is claimed is:

- 15 The combination with a swinging door having cut-away portions in opposite vertical edges at the bottom thereof, of angle plates secured to the door for forming housings to the cut-away portions, the said door being formed with a vertical slot opening at opposite ends into the cut-away portions, a threshold strip slidable in the slot, racks fixed to opposite ends of the strip and movable within the cut-away portion, a toothed

gear meshing with one of the racks, a 25 toothed segment meshing with the other rack, a shaft supported by the door and connecting the respective gear and segment to permit movement thereof in unison, a link pivoted to the segment, a spring fixed with 30 in one of the cut-away portions in the door and connected with the link for exerting a pull thereon whereby the threshold strip will be normally elevated within the slot, and a stationary abutment rack fixed to the 35 door frame and disposed at right angles to the threshold strip and also above the gear for meshing engagement therewith and adapted to operate the latter on the closing of the door for projecting the threshold 40 strip without the slot.

In testimony whereof I affix my signature in presence of two witnesses.

EMIL YOUNGQUIST.
